UNITED STATES PATENT OFFICE

159,054

COMB HOLDER

Xuma J. Doty, Los Angeles, Calif.

Application October 20, 1949, Serial No. 5,597

Term of patent 14 years

(Cl. D86—10)

To all whom it may concern:

Be it known that I, Xuma J. Doty, a citizen of the United States, residing in the city and county of Los Angeles and State of California, have invented a new, original, and ornamental Design for a Comb Holder, of which the following is a specification, reference being had to the accompanying drawing, forming part thereof.

Fig. 1 is a perspective view of a comb holder, showing my new design.

Fig. 2 is a side elevation.

Fig. 3 is a top plan view.

Fig. 4 is a bottom plan view.

Fig. 5 is an end view.

I claim:

The ornamental design for a comb holder, substantially as shown.

XUMA J. DOTY.
